UNITED STATES PATENT OFFICE.

WILLIAM L. AXIUM, OF DOWNTON GROVE, ILLINOIS.

FORM FOR CONCRETE CONSTRUCTION.

No. 907,438.

Specification of Letters Patent.

Patented Dec. 22, 1908.

Application filed December 30, 1907. Serial No. 408,573.

To all whom it may concern:

Be it known that I, WILLIAM L. AXIUM, a citizen of the United States, residing at Downers Grove, county of DuPage, and State of Illinois, have invented certain new and useful Improvements in Forms for Concrete Construction, of which the following is a specification.

My invention relates to concrete construction and particularly to forms for concrete construction.

The forms generally used for concrete construction are usually made of wood which necessitates the making of new forms as the work progresses, as the wooden forms soon become warped and broken to such an extent as to become practically useless. Also, separate forms must be made for each variation in the size of the columns and beams.

20 The object of my invention is to provide a form for concrete construction which may be used repeatedly without deteriorating in quality or efficiency.

25 A further object of my invention is to provide a form for concrete construction which may be readily and quickly adjusted for the construction of various sizes of columns, beams and the like.

30 Other objects will appear hereinafter.

35 With these objects in view my invention consists generally in a light but rigid skeleton steel frame of substantially the size and form required and a suitable lining for said frame to receive the concrete.

40 My invention further consists in a plurality of longitudinal members suitably arranged to give the proper configuration to the form and connected by a plurality of transverse members to form a rigid frame and in sheet metal members adapted to line said frame to receive the concrete.

45 My invention further consists in a frame comprising a plurality of longitudinal steel members adjustably connected by a plurality of transverse members and a suitable lining, for said frame.

50 My invention further consists in a frame as mentioned in combination with a similar extension member detachably connected thereto.

55 My invention further consists in a frame as mentioned in combination with a similar extension frame, means slidably connecting the frame and the extension, and in suitable members for closing the gaps between them.

My invention further consists in various

details of construction and arrangements of parts all as will be hereinafter fully described and particularly pointed out in the claims.

My invention will be more readily understood by reference to the accompanying drawings forming a part of this specification and in which—

Figure 1 is a side elevation of the upper end of a form for a column illustrating the beam forms connected thereto by suitable quoins. Fig. 2 is a side elevation of one of the forms for a beam. Fig. 3 is a similar view with the parts expanded to form a beam of larger dimensions. Fig. 4 is a section of the form on the line $x-x$ of Fig. 3. Fig. 5 is a detail side elevation illustrating one manner of extending the length of the beam form. Fig. 6 is a detail plan view of a form for a main beam equipped or having connected thereto form frames for smaller cross or intermediate beams. Fig. 7 is a side elevation of a column form with an extension member slidably connected thereto and illustrating a closure to complete the form between the sections of the column. Fig. 8 is a cross section of a column form upon an enlarged scale. Fig. 9 is a detail cross section of a column form arranged for an octagonal column. Fig. 10 is a perspective view of a couple of quoins arranged at the upper end of a column form, and Fig. 11 is a detail.

In the drawings, I have illustrated the preferred embodiment of my invention, and in describing the same in detail will first describe the forms for the beams and then the forms for the columns and the manner of connecting the two.

As illustrated in the drawings the frame for the beam forms consists of a plurality of longitudinal steel members arranged to form a trough like device and suitably connected by transverse members into a rigid frame. The longitudinal members preferably comprise the top, T irons 1—1, the angle irons, 2—2, and the intermediate bars, 3—3 and 4, the former being arranged at the sides intermediate of the top members, 1 and the bottom members, 2, and the latter being arranged at the bottom of the device between the members, 2—2. The members, 1 to 4 are rigidly connected by a plurality of transverse members, 5. These are riveted in pairs to the intermediate members, 3 and 4, and diagonally arranged as shown to rigidly brace the members, apart. The ends of the members, 5 are bolted to the members, 1 and

2, said members being provided with a plurality of bolt holes, 6, 7 and 8. By adjusting the bolts in the various bolt holes, the distance between the members may be varied. 5 The device is so proportioned that when the bolts are in the bolt holes, 6, the form will be adjusted for the smallest size beams. By arranging the bolts in the holes, 7, it is obvious that the form will be enlarged to construct a beam of greater dimensions, and in 10 the holes, 8 for a beam of still larger dimensions.

It is obvious that any number of bolt holes may be provided, the greater the number, 15 the greater the adjustment of the form. However, a few are generally sufficient, and these are preferably so placed as to adjust the form to standard sizes. If preferred the top members, 1 may be constructed of angle irons 20 but I prefer the T irons as shown, the upper flange, 1' preferably being the same height as the thickness of the floor which is to be laid. To close the frame to complete the form, I provide the members, 9 and 10 which are 25 preferably formed of sheet metal, the frame supporting the same in such a manner as to give sufficient rigidity thereto.

In order that the device may be used in the construction of beams of any desired length, 30 I construct the same of longitudinal members of a length equal to the shortest beams which are made in actual practice and provide the same with extension members by means of which it may be adjusted for use in 35 forming the beams of any desired length. The extension members are formed similarly to the main portion and may be bolted thereto, the ends of the members being flanged for this purpose, or they may be slidably connected thereto. In the latter instance the 40 extension member is provided with a plurality of extension bars slidably arranged between the longitudinal and transverse members of the main portion of the device, as 45 shown in Fig. 5. In said figure the longitudinal members of the extension member are indicated at 1^a, 2^a, and 3^a. Bolted to the transverse members, 5^a or otherwise secured thereto are the extension bars, 11 50 which extend a considerable distance into the main portion of the frame between its component members. The main and extension members of the frame are thus adjustably connected and may be extended to 55 any length desired, limited only by the length of the bars, 11. After the frame is extended, the gaps or spaces between the ends of the members are closed by similar members, 1^b, 2^b, and 3^b of suitable length and connected 60 by the transverse members, 5^b. The ends of the longitudinal members of the several parts are provided with corresponding flanges, or lugs, 12 by which they may be bolted together forming a rigid frame. If deemed

necessary a truss member, 13 may be employed to strengthen the joint. 65

The form frames for the columns are adjustable in size to vary the dimensions of the columns, and are so constructed that they may be used in constructing either square or 70 octagonal columns. To this end they are formed of separate sides which are adjustable in width and provided with means for connecting their adjacent edges. Each side consists of three longitudinally disposed strips, 75 14—14 and 15, the strips, 14, forming the edges and the strip, 15, being the intermediate strip, and a plurality of transverse members 16 riveted to the strip, 15 and bolted to the strip, 14. The transverse members, 16 80 are similar to the members, 5 of the beam form frames and the width of the device may be adjusted in a manner similar to the adjustment of the beam frames, the members, 14 being provided with a plurality of bolt 85 holes, 17 for this purpose. The edges of the sides are provided with means for locking the sides together. This preferably consists of a plurality of lugs, 18 formed upon or secured to the strips, 14. The lugs are provided with 90 bolt holes which register when the sides are assembled and the frame is held together by the bolts, 19 passing through the lugs. In constructing an octagonal column suitable members, 20 may be interposed between the 95 edges of the members, 14. These may be plates provided with lugs, 21 to register with the lug, 18 as shown in Fig. 9, or may be formed similarly to the adjustable sides of the column form frame. It is obvious that 100 the device may be so proportioned as to be adjustable to form columns of any size and that by the arrangement and adjustment of the sides, columns of various forms may be constructed. The length of the members, 105 14 and 15 are proportioned to construct columns of minimum height, and to utilize the same for columns of greater height, I provide suitable extension members and in Fig. 7 I have illustrated the preferred manner of extending their length. The extension member 110 comprises adjustable sides formed similarly to the column portion of the longitudinal strips, 14' and 15' adjustably connected by the transverse members, 16'. Secured to 115 the extension members are the extension strips, 22 which telescope between the strips, 14 and the transverse members or braces, 16. It is evident that the frame may be thus extended to any desired length limited only by 120 the length of the strips, 22. To complete the frame, I provide suitable means for closing the gaps between the strips, 14 and 15 and the corresponding strips 14' and 15'. These consist of short sections formed similarly to 125 the sides of the main portion of the frame and composed of the strips, 14^b and 15^b connected by the transverse members 16^b. It is ob-

vious that the transverse members, 16 may be arranged upon both the inner and outer sides of the strips 14 and 15 or upon one side only, the former construction being illustrated in Fig. 9 and the latter in Fig. 8. This applies also to the transverse members, 5 of the beam form frames. The form for the columns is completed by the lining members, 23 preferably formed of sheet metal.

10 To connect the beam forms to the column forms, I provide suitable quoins forms as illustrated in Figs. 1 and 10. Each quoins form comprises a pair of side plates 24—24 of sufficient size to be used in constructing 15 quoins of largest dimensions and provided with the flanges 25 and 26 by which they are connected to the ends of the beam and column forms respectively. The flanges, 25 are provided with a plurality of bolt holes, 20 27 arranged to register with the bolt holes in the end flanges, 28 of the beam forms when in their several adjusted positions. The bottom of the form is adjustably fixed between the plates, 24 in order to be raised or lowered 25 to suit the depth of the beam forms; and is preferably adjustable in width to vary the width of the quoins form to correspond with the adjustment in width of the beam forms and column form. To this end the bottom 30 comprises the angle irons, 29 adapted to be bolted to the plates, 24, the intermediate strips, 30 and the transverse members, 31, adjustably connected in a manner similar to the several members of the beam and column 35 forms.

Sometimes it is desirable to construct small intermediate cross beams extending between those of larger size or the main beams. To this end I provide the beam 40 forms, 32 formed similarly to the main beam forms but of smaller dimensions. These are provided with flanges, 33 by which they are connected to the main beam forms, the latter being flanged in the proper places as at 45 for this purpose.

The concrete form herein described is of simple construction and of comparatively low cost, that is although the initial cost is somewhat greater than that of the wooden 50 one now in general use, the actual cost is much less, inasmuch as the wooden forms need to be constantly replaced while the steel forms may be used repeatedly without deteriorating in quality or efficiency. Further, a few forms are all that is necessary in 55 constructing a building. The forms may be adjusted to one of their larger sizes in constructing the lower stories of a building and as the work progresses may be removed to 60 the upper stories and reduced in size as necessary.

Having described my invention what I

claim as new and desire to secure by Letters Patent is:

1. A form for concrete beams and columns comprising a skeleton frame formed of a plurality of longitudinal members rigidly connected by a plurality of angularly disposed transverse members and a suitable lining for said frame, said form being adjustable by changing the angular positions of said transverse members substantially as described.

2. A form for concrete construction comprising a frame formed of a plurality of longitudinal members rigidly connected by a plurality of diagonally disposed transverse members, said transverse members being permanently secured to certain of the longitudinal members and adjustably connected to others of said longitudinal members and a suitable lining for said frame, substantially as and for the purpose specified.

3. A form for concrete construction comprising a frame the sides of which being formed of three parallel longitudinal members connected by diagonally disposed transverse members, said transverse members being permanently secured to the central longitudinal member and adjustably secured to the other longitudinal members, the other longitudinal members being provided with a plurality of bolt holes, and a lining for said frame substantially as described.

4. A form for concrete construction comprising a beam form consisting of a plurality of longitudinal frame members adjustably connected and a lining for said beam form, the ends of said longitudinal members being turned and perforated, in combination with a quoins form consisting of a pair of side plates, an adjustable bottom connecting said plates and a lining for said bottom, the edges of said side plates being outwardly bent to form flanges, and said flanges being perforated to receive bolts for attaching the perforated ends of said longitudinal frame members thereto, substantially as described.

5. A quoins form for concrete construction comprising a pair of side plates provided with flanges for attaching the same to beam and column forms, and a bottom consisting of a pair of longitudinal members adjustably connected to the respective side plates, a plurality of transverse members adjustably connecting said longitudinal members and a lining resting on said members, substantially as described.

In testimony whereof I have signed my name to this specification in the presence of two subscribing witnesses.

WILLIAM L. AXIUM.
